(57) **CLAIM**

The ornamental design for a chopper, as shown and described.

DESCRIPTION

FIG. 1 is a front elevation view of a chopper showing my new design, the opposite side being the same;

FIG. 2 is a left side elevation view thereof, the opposite side being the same;

FIG. 3 is a left side elevation view of FIG. 2 with the base removed for clarity of illustration;

FIG. 4 is a top perspective view of FIG. 1;

FIG. 5 is a bottom perspective view of FIG. 3; and,

FIG. 6 is a top plan view of FIG. 1.

The undisclosed bottom view is plane and unornamented.
